UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

SORTING-MACHINE STOP DEVICE.

Application filed June 29, 1922, Serial No. 571,745. Renewed May 26, 1923.

To all whom it may concern:

Be it known that I, WILLIAM W. LASKER, a citizen of the United States, residing in Brooklyn, in the county of Kings and State of New York, have invented certain new and useful Improvements in Sorting-Machine Stop Devices, of which the following is a specification.

My present invention relates to stop devices for machines for sorting or classifying perforated cards such, for example, as are used in automatic calculating and adding machines, and more particularly to machines of the general character or type disclosed in Letters Patent No. 1,315,370, dated September 9, 1919.

For the purpose of illustration I have shown an embodiment of my invention as it would be applied to the machine described and illustrated in application Serial No. 544,417, filed by me March 17, 1922.

My present invention will best be understood from the following description and the appended drawings, in which, Figure 1 is a partial sectional elevation of the machine shown in said copending application with one embodiment of my invention applied thereto; Fig. 2 is a section on the line 2—2 of Fig. 1; Fig. 3 is a view through the switch-controlling box with the cover removed; Fig. 4 is a side elevation of some of the parts shown in Fig. 3, and Fig. 5 is a modification.

Like reference characters refer to like parts in the several views.

Referring, now, to the drawings, the machine is carried on side plates 1, connected by tie rods 2. These plates support, in the illustrated embodiment, the feeding mechanism, analyzing mechanism and associated parts.

For an understanding of my present invention, it will be unnecessary to redescribe the machine, as it is fully described in the said copending application, but it will be sufficient here to note that the cards are carried in a hopper 3. From this hopper they are moved one at a time by a picker blade 14 on a block 4, which carries the cards one at a time to an adjustable opening 15 through a pair of rollers 16, 18, connected, respectively, to driving shafts 17, 19. By these rollers the cards are passed into the analyzing mechanism, some parts

of which I have designated, as at 48, and from thence the cards pass to rollers 33 on shafts 34, 35, by which rollers they are forwarded to the hoppers. The picker blade 14 is moved by an eccentric 12 on the shaft 13 through a link 11 connected to a lever 7 on the shaft 8.

A plurality of hoppers 112 have extending over each of them guide members 124 connected to a shaft 117, this guide member having a deflecting finger 125 on the lower part thereof. On the shaft 117 there may be one or more rollers 116 turning loosely thereon, and cooperating with these rollers are rollers 115 on shafts 113, these latter shafts being driven from the machine.

On an outer end of each of the shafts 117 is an operating arm 154, this arm, as shown best in Fig. 1, constituting a lever, the rotation of which will serve to move the guide member 124 from the full line to the dotted line position shown in the second hopper.

In normal operation, the guides 124 are in full line position, so that a card may pass over a hopper when the guide member 124 is in this position. If the arm 154 be rotated over one hopper, however, the guide member will be thrown to the dotted line position shown over the second hopper in Fig. 1, and the card will thereupon be deflected by the deflector 125 and pass into that hopper. In other words, the hoppers are arranged with guide and deflecting devices so that a card may be dropped into any predetermined hopper in accordance with the characteristics of the card, as fully explained in the said copending application.

In Fig. 2 I have reproduced a portion of this selecting mechanism which determines the hopper into which a given card is to be dropped, such mechanism consisting of a timing disc 140 rotating with the driving shaft 128 and carrying a plurality of cams 142 pivoted at 141, and each having a cam surface 143 adapted to cooperate with a pin 160 which is moved into cooperating position by mechanism in the analyzing heads 48, as fully explained in the said copending application. When a given cam 143 is contacted by the pin 160, the outer end of the cam 142 is thrown outward and is held in that position by means of springs 152 which pull the cam slides 149, 150, so

that the locking portion 149 will rest on a pin 151 mounted on the disc 140. This will hold the cam 142 and its roller 153 in an outward position to engage with the under side of the arm 154 to rotate the same and turn the corresponding guide 125 to the dotted line position of Fig. 1. It will be understood that there would be one of these operating mechanisms for each of the 10 card-receiving hoppers.

In the hoppers the cards fall on a bottom plate 200 supported by a spring 201 and guided by a rod 202 fastened to the plate 200 and passing through holes in the members 203 and 204, so that the weight of the cards as they accumulate will gradually depress the plate 200 by the collapsing of the spring 201. For any given quantity of cards, therefore, the position of the plate 200 will be determined by the number of cards which have been dropped into the hopper.

In the machine in connection with which I have shown my invention, the distribution of the cards in several hoppers may be, however, regulated, so that one hopper may fill up very quickly, so that close attention on the part of the operator under such circumstances may be required to prevent injury to the machine or to the cards. By my invention I provide means by which the machine will be stopped when any hopper shall have received a predetermined number of cards, or, what is the same thing, has been filled to a predetermined point. In the present embodiment of my machine, I utilize the weight of such a pile of cards to determine when the machine shall be stopped, but it is obvious that I could use the height of the pile as a matter of distance, instead of weight, if desired.

Extending parallel with the receiving hoppers 112 is a rock shaft 205 supported in brackets 206 fastened to tie rods 207 extending longitudinally of the machine. On the shaft 205 there is a lever 208 having an upwardly projecting finger 209 arranged to contact with the plate 200 as the latter is pushed down by the weight of the cards resting on it. There will be one of these levers 208 for each of the hoppers, so that the depression of any lever will rock the shaft 205 clockwise in Fig. 2.

In the specific embodiment of my invention I have used, for purposes of illustration, a switch which may form part of the starting and stopping mechanism for the machine. A preferred form of switch is shown in Fig. 3, and as being a two-pole switch in which the switch arm is thrown to a closed position by a spring and held in that position against the action of another spring for throwing the switch to its open position. 165* is a box carried by the frame-work and provided with two binding

posts or contacts 166, 166 forming part of the circuit which includes the driving motor for the machine (not shown) and a source of current for said motor (also not shown). The two posts or contacts 166, 166 are engaged by a switch arm 167 pivoted at 168, when the motor is to be started, and disengaged from the posts or contacts when the motor is to be stopped. The dotted lines in Fig. 3 indicate the positions of the several 75 parts of the switch when it is in "open position" and the full lines the positions of the parts when the switch is in "closed position." The switch arm 167 is moved from its dotted line position to its full line position by the depression of a button 169, the rod of which is connected to a lever 170, which is pivoted at 168. The lever 170 is connected with the switch arm 167 by a spring 170*, which when it is put under tension by the movement of the lever 170, pulls the switch arm 167 towards its full line position. The parts are so arranged that the switch arm 167 can only be moved by the spring 170* to its "closed position" by a 80 full or complete movement of the button 169, and this is taken care of as follows: The switch arm 167 carries a pawl 187, which, as the switch arm is moved towards its closed position engages a shoulder 188 85 on a trigger lever 173 pivoted at 173*, the pawl 187 being held in engagement with the shoulder (until released) by means of a spring 189 which is connected with the pawl 187 and the switch arm. When this engagement occurs, the switch arm 167 has not bridged the contacts 166, 166. A continued depression of the button 169 causes an arm 167* carried by the switch arm 167 to engage the arm 187* of the pawl 187 to rock 100 the pawl on its pivot 187* out of engagement with the shoulder 188, thereby permitting the spring 170 to finally move the switch arm 167 to its "closed position" across the posts or contacts 166, 166. In order to hold 110 the switch arm in its "closed position" against the action of the spring 174, which is for the purpose of throwing the switch arm 167 to its "open position" (dotted line position), and which is put under tension 115 upon the depression of button 169, the lever 170 is provided with a detent 171 which engages a notch 171* in the lever 173, this engagement being insured through the action of spring 189.

The locking lever 173 has an arm 186 projecting therefrom through the wall of the casing 165, and extending above the outer end of the arm 186 is the arm 185 of a lever 183 pivoted at 184 and having its 125 opposite end extending through a slot formed between a projection 210 and the face of a fork 211 connected to a lever 212 fastened to the shaft 205. A slot may be provided between the lever 212 and the 130

fork 211 to take care of any inequalities in workmanship or the like.

With the parts in the position shown in full lines in Figs. 3 and 4, the machine will be in operation and cards will be passing from the hopper 3 through the analyzing mechanism and into the receiving hoppers. As they accumulate in the hoppers 112, the plates 200 will be gradually depressed by the added weight, and when any one of the plates has reached a predetermined position, such as is shown in dotted lines in the second hopper in Fig. 1, the end 209 of the lever 208 will be contacted to rotate the shaft 205, which will raise the fork 211 and rotate the lever 183 to cause its end 185 to depress the end of the projection 186 on the locking lever 173. This will throw the lever 173 to the left of Fig. 3 and take its notch 171^a away from the end of the detent 171 to permit the spring 174 to move the switch arm 167 through contact of the pin 170^b with the switch arm 167 into the open or dotted line position of Fig. 3 to bring the machine to a stop. The cards can be then removed from the filled hopper and the machine started again. If desired the machine may be stopped manually by rocking the lever 173 to the left on its pivot 173^a.

In Fig. 5 I have shown a modification of the lever 208, by which the predetermined point at which the machine shall be stopped can be regulated. To this end I substitute for the lever 208, shown in Fig. 2, a lever 213 having at its outer end a rod 214 held adjustable by a screw 215. It will be obvious that when the rod 214 is shifted to the end of the lever 213, the point to which the plate 200 must fall before rotating the shaft 205 to stop the machine may, in turn, be regulated.

It is obvious that my invention may be widely varied in its embodiments, and that the arrangement which I have shown is merely illustrative.

I claim:

1. In an apparatus of the class described, a card-receiving hopper, power actuated means to forward cards one at a time to the receiving hopper, and means to stop the operation of said power actuated means when the number of cards in the receiving hopper has reached a predetermined number.

2. In an apparatus of the class described, a card-receiving hopper, power actuated means to forward cards one at a time to the receiving hopper, means to stop the operation of said power actuated means when the number of cards in the receiving hopper has reached a predetermined number, and means whereby the number of cards required to operate said stopping means may be varied.

3. In an apparatus of the class described, a plurality of card-receiving hoppers, power

actuated means to forward cards one at a time to the receiving hoppers and to distribute the cards in said receiving hoppers in accordance with the individual characteristics of the cards, and means to stop the operation of said power actuated means when the number of cards in any one of the receiving hoppers has reached a predetermined number. 70

4. In an apparatus of the class described, a plurality of card-receiving hoppers, power actuated means to forward cards one at a time to the receiving hoppers and to distribute the cards in said receiving hoppers in accordance with the individual characteristics of the cards, means to stop the operation of said power actuated means when the number of cards in any one of the receiving hoppers has reached a predetermined number, and means whereby the number of cards to operate said stopping means may be regulated. 75

5. In an apparatus of the class described, a card-receiving hopper comprising a receptacle having a vertically movable bottom, power actuated means to forward cards one at a time towards and into said hopper to be supported on said bottom, said bottom being arranged to be depressed by the weight of the cards upon it, and means to suspend the operation of said power actuated means when the bottom has been depressed to a predetermined point. 80

6. In an apparatus of the class described, a card-receiving hopper comprising a receptacle having a vertically movable bottom, power actuated means to forward cards one at a time towards and into said hopper to be supported on said bottom, said bottom being arranged to be depressed by the weight of the cards upon it, means to suspend the operation of said power actuated means when the bottom has been depressed to a predetermined point, and means whereby the stop operating position of the bottom may be regulated. 85

7. In an apparatus of the class described, a plurality of card-receiving hoppers, each comprising a receptacle having a vertically movable bottom, power actuated means to forward cards one at a time towards and into said hoppers and to distribute the cards in said receiving hoppers in accordance with the individual characteristics of the cards, each of said bottoms being arranged to be depressed by the weight of the cards upon it, and means to stop the operation of said power actuated means when the bottom of any one of said hoppers has been depressed to a predetermined point. 110

8. In an apparatus of the class described, a plurality of card-receiving hoppers, each comprising a receptacle having a vertically movable bottom, power actuated means to forward cards one at a time towards and into

said hoppers and to distribute the cards in said receiving hoppers in accordance with the individual characteristics of the cards, each of said bottoms being arranged to be depressed by the weight of the cards upon it, means to stop the operation of said power actuated means when the bottom of any one of said hoppers has been depressed to a predetermined point, and means whereby the 10 stopping position of each bottom may be regulated.

5 a card receiving hopper having a movable bottom; power actuated means to forward cards, one at a time, towards and into said hopper to be supported on said bottom which is moved as the cards are successively put upon it; means for starting and stopping the said power actuated means including a switch; and means operated by the movement of said bottom to actuate the switch to stop the power actuated means when the bottom has moved to a predetermined point.

15 20

9. In an apparatus of the class described,

WILLIAM W. LASKER.
